UNITED STATES PATENT OFFICE.

EDGAR W. CLEVELAND, OF HOLLAND, MICHIGAN.

ADJUSTABLE ARM FOR MULTIPLE DRILLS.

1,316,140.

Specification of Letters Patent. Patented Sept. 16, 1919.

Application filed March 12, 1919. Serial No. 282,223.

To all whom it may concern:

Be it known that I, EDGAR W. CLEVELAND, a citizen of the United States of America, residing at Holland, in the county of Ottawa and State of Michigan, have invented 5 certain new and useful Improvements in Adjustable Arms for Multiple Drills; and I do hereby declare the following to be a full, clear, and exact description of the invention, such as will enable others skilled in the art to which it appertains to make and use the same.

This invention relates to improvements in adjustable arms for multiple spindle drills. 15 In such construction, a plurality of arms are used to carry drills, the arms being adjustably mounted on a common head, and each arm carries at its end a vertically adjustable journal box in which a drill spindle is 20 rotatably mounted, and in practice all of the spindles are driven from a common source of power. The drills usually are of varied lengths, and it is many times necessary to drill holes of different depths, making it 25 imperative that the journal boxes be vertically adjustable on their respective arms, and it is further necessary that such journal boxes shall be quickly and easily adjustable, and firmly held in any position to which 30 adjusted. By reason of the fact that such drill spindles are frequently placed closely together, it is necessary that the adjusting means shall be accessible for adjustment and changes. The present invention has for its 35 object and purpose, the attainment of all of these desired ends by means of a construction which is simple to manufacture, yet especially effective in operation. Many other objects and purposes other than that 40 stated will appear as understanding of the invention is had from the following description, taken in connection with the accompanying drawing, in which,

Figure 1 is a fragmentary sectional view 45 showing one preferred form of adjusting device for the journal box on an arm of a multiple spindle drill.

Fig. 2 is a horizontal section taken on the line 2—2, of Fig. 1.

50 Fig. 3 is a view, to reduced scale, and similar to Fig. 1 of a modified form for serving the same purpose.

Fig. 4 is a horizontal section on the line 4—4, Fig. 2.

55 Fig. 5 illustrates a still further modifica-

tion in form of equalizing adjustment bar for the journal box, and

Fig. 6 is an elevation of the bar used in Fig. 5.

Like references refer to like parts in the 60 different views of the drawing.

The arms on which the drill spindle journal boxes are mounted comprise spaced apart sides 1 which are integrally connected at one end by a portion 2 in which, in the 65 form shown in Fig. 1, two spaced apart vertical slots 3 are cut. The opposite end of the arm is not shown in the drawing, but is of the usual and well known construction, similar, for instance to that shown in my 70 previous Patent No. 1,082,009.

A block 4 is fitted to slide vertically on the end 2 of the arm, and integral therewith is a sleeve 5 which serves as the journal box in which the drill spindle 6 is rotatably 75 mounted, the same carrying a drill receiving socket 7 at its lower end below the journal box. The block 4 is adjustably connected to the arm by bolts 8 which have heads 9 as shown, the bolts passing through the slots 3 of the arm while the heads 9 are located within the block 4 and between the same a cylindrical pin or rod 10 is positioned, the ends of which are cut at oppositely inclined bevels as indicated at 11 and bear against 80 correspondingly cut inclines on the heads 9. The rod 10 is entered into the block 4 through a vertical opening 12 bored the entire length of the block substantially parallel to the axis of the spindle 6; while the 85 bolts 8 and heads 9 thereof are placed in position by inserting the same through transverse openings 13 bored adjacent the upper end and lower end of the journal box, as shown. A bar 14 having openings adjacent its ends to pass the bolts 8 is placed over said bolts and against the inner side of the end 2 of the arm and nuts 15 are 90 threaded on to the ends of the bolts to draw the journal box and the block 4 integrally 100 formed therewith tightly against the arm so as to fix the same against movement with respect to the arm. The bar 14 is the equivalent of two washers, one around each bolt 14 and it is obvious that the bar may be replaced by such washers.

With this construction, it is obvious that the nuts 15 on the lower bolt 8 are readily accessible for tightening or loosening, but that the nuts on the upper bolt cannot be 110

operated as readily, particularly when the arm is attached to a drill head which lies above the arm and more or less covers the arm so that access to the upper nuts 15 is almost impossible. This is true of practically all forms of drill arms. However, as soon as the lower nuts 15 are loosened and the lower bolt released, the rod 10 is allowed to drop slightly, this serving to release the upper bolt without changing the nuts 15 thereon and the journal box may then be moved within the limits prescribed by the length of the slots 3. As soon as the box is properly positioned, the lower nuts 15 are tightened, drawing the head 9 of the lower bolt against the bevel 11 at the lower end of rod 10 and causing the rod to be elevated so that its upper end similarly but oppositely beveled engages against head 9 of the upper bolt, and causing a simultaneous and equal tightening of both the upper and lower ends of the journal box against the end of the arm. The operation of the lower nuts 15 is all that is required in any case for effecting a change of position of the journal box with reference to the arm, a simultaneous loosening or tightening of the strain on both bolts 8 being effected by loosening or tightening the lower nuts on the lower bolt alone.

This construction is very effective and has the further merit that it is completely housed and disguised from sight. The construction is simple and all strains transmitted are in the direction of the length of the members acted upon so that no bending or buckling of the same is possible. The housing of the rod 10 provides a support for the same throughout its length which precludes any buckling of the same. There is nothing to get out of order, and the adjustment desired can be quickly and readily effected as the nut 15 on the lower bolt 8 is always readily accessible whatever the position of the arm and no matter how closely associated with the other arms on the machine.

In Figs. 3 and 4, a modified form of the invention is shown. The slots 3 in the end of the arm are eliminated and a T-slot 16 is cut lengthwise of and in the side of the block 4 next to the end of the arm and heads 17 of T-bolts 18 are located in said blocks which take the place of the bolts 8. The bolts 18 pass through bushings 19 which are inserted in openings 20 bored into the end 2^a of the arm. A shorter rod 10^a having beveled ends 11^a is located in an opening 21 bored vertically from the bottom in the end 2^a of the arm, said rod being disposed between the ends of the bushings 19 which are cut at an incline to correspond with the beveled portions 11^a of the bushings. A nut 15^a threads on to the end of each of the bolts 18 and against the bushings.

65 The operation of loosening and tightening

the lower nut for release of the journal box is the same as in the former construction, and the adjustment is the same except that the box is moved up or down, the heads 17 changing position in the slot 16, instead of the bolts moving back and forth in slots in the end of the arm as before. In all other respects the operation is the same, and the same advantages are present.

In Figs. 5 and 6 a further modification is partially illustrated. A bar 22 is placed directly against the inner side of the end 2^a or end 2 of the arm, shown in Figs. 3 and 1, and the bolts 18 pass through openings slightly elongated and countersunk as indicated at 23. Bushings 24 having tapered sides to seat in the countersunk portions of the openings are placed around the bolts 18 and nuts 15^b thread on to the bolts. The elongation of the openings 23 permits a slight movement of the bar 22 up and down when the lower nuts are loosened, and there is a clearance between the upper side of the upper bushing and the countersunk part of the opening in which it is seated, and a similar clearance between the lower portion of the lower bushing and the countersunk recess in which it is seated when the nuts are tightened. From this construction, it is apparent that the adjustment of the journal box may be effected by loosening the lower nut on the lower bolt as before, and this construction is applicable to either of the forms of arms shown in both Figs. 1 and 3. This construction is more economical to make than either of the others as the bushings 24 are a screw machine product, and there is no need to bore openings such as are necessary to receive the pins 10 and 10^a. The principle of operation is the same, however, and with this construction, as well as the others, the lower nut is accessible and may be quickly and readily worked to accomplish the adjustment, and the bar 22 is movable lengthwise the same as the pins 10 or rods 10 and 10^a when the lower bolt is tightened to effect a simultaneous and equal tightening of the upper bolt.

I claim:

1. An adjustable arm for multiple spindle drills, comprising an arm, a vertically adjustable journal box at one end of the arm, a member formed with oppositely beveled ends disposed vertically, bolts connecting the journal box to the arm, and means on said bolts for engaging the ends of said member to move the same vertically whereby the box may be released or secured in place by loosening or tightening one only of the bolts, substantially as described.

2. An adjustable arm for multiple spindle drills, comprising an arm, a journal box located at one end of and against the arm, bolts for attaching the box to the arm, a member having oppositely cut inclined ends

130

disposed between the bolts, and devices on the bolts engaging the inclined ends of said member whereby release of one bolt simultaneously releases the other for freeing the 5 journal box for adjustment with respect to the arm.

3. An adjustable arm for multiple spindle drills, comprising an arm, a journal box located at one end of and against the arm, 10 bolts disposed one over the other and connecting the box and the arm, a member disposed between the bolts, and devices on said bolts adapted to be operated against the ends of said members to move the same vertically as a bolt is tightened or away from the ends of the member as the bolts are released, whereby tightening or loosening of one of the bolts will simultaneously tighten or loosen the other bolt, substantially as 15 described.

4. An adjustable arm for multiple spindle drills, comprising an arm, a journal box located at one end of the arm, bolts disposed one over the other and connecting the box 25 to the arm, a member disposed vertically between the bolts and formed with ends cut at an incline and in opposite directions at one side thereof, and a head on each bolt cut to bear against the inclines on the member, 30 whereby tightening or loosening of one of the bolts simultaneously tightens or loosens the other bolt.

5. An adjustable drill supporting arm comprising an arm, a journal box having 35 a vertical opening therethrough positioned against the end of the arm, a rod having its upper and lower ends cut at oppositely extending bevels at one side of the rod, upper

and lower bolts having their heads located within the box and extending therefrom 40 through the arm, said heads bearing against the beveled ends of the rod, and a nut threaded on to the end of each bolt, substantially as described.

6. An adjustable drill supporting arm 45 comprising an arm having spaced apart sides connected by an integral portion at one end, said portion having upper and lower vertical slots cut therein, a journal box formed with a vertical opening there- 50 through and upper and lower transverse openings extending from the front of the box to the vertical opening therein, a headed bolt entered into each transverse opening, through the box and through a slot in the 55 end of the arm, a rod formed with oppositely extending beveled ends located in said vertical opening in the box between the heads of the bolts, said heads bearing against the beveled ends of the rod, and a nut on 60 the end of each bolt to tighten the bolts and fix the box against movement with respect to the arm.

7. An adjustable arm for multiple spindle drills, comprising an arm, a journal box 65 located against one end of the arm, bolts for attaching the box to the arm, a vertical member disposed between the bolts, and means operated by the bolts as either one is tightened to move the member vertically 70 against the similar means on the other bolt, thereby tightening both bolts simultaneously as either one is tightened, or vice versa, substantially as described.

In testimony whereof I affix my signature. 75
